UNITED STATES PATENT OFFICE.

CHRISTOPHER H. BIERBAUM, OF BUFFALO, NEW YORK.

CASTING-MACHINE.

No. 830,199.

Specification of Letters Patent.

Patented Sept. 4, 1906.

Application filed December 6, 1902. Serial No. 134,209.

To all whom it may concern:

Be it known that I, CHRISTOPHER H. BIERBAUM, a citizen of the United States, residing at Buffalo, in the county of Erie and State 5 of New York, have invented new and useful Improvements in Casting-Machines, of which the following is a specification.

This invention relates more particularly to a machine for casting in a metal mold that 10 class of metals and alloys in which the maximum shrinkage occurs at nearly the same temperature at which solidification takes place.

The object of this invention is to produce a 15 machine whereby full and perfect castings of metal having this characteristic can be produced economically and expeditiously.

In the accompanying drawings consisting of three sheets, Figure 1 is a side elevation of my 20 improved casting-machine, showing the same in position ready for making a casting. Fig. 2 is a top plan view of the same. Fig. 3 is a vertical longitudinal section of the machine, showing the mold and connecting parts 25 tilted into the position for beginning casting. Fig. 4 is a vertical cross-section in line 4 4, Fig. 1. Fig. 5 is a perspective view of a flanged half-bearing or semicylindrical lining for bearings which is cast in the mold shown 30 in the machine. Figs. 6 and 7 are vertical transverse sections, on an enlarged scale, in lines 6 6 and 7 7, Fig. 1, respectively, showing the position of the mold at the beginning 35 and ending of the casting operation. Fig. 8 is a fragmentary vertical longitudinal section, on an enlarged scale, in line 8 8, Fig. 2. Fig. 9 is a horizontal longitudinal section in line 9 9, Fig. 8.

Similar letters of reference indicate corresponding parts throughout the several views.

As shown in Fig. 5, the half-bearing casting, which is produced in the mold in the machine, consists of a semicylindrical body or shell A, having a peripheral flange a at one 45 end. The mold is constructed wholly of metal and consists, essentially, of a disk-shaped cover, face-plate, or rear section B, an inner semicylindrical body-section C, an outer semicylindrical body-section D, a semi- 50 cylindrical or crescent-shaped flange-section E, and bottom section F. The parts of the mold are movably supported in such manner that all of the same can be tilted, and all the parts excepting the front section B can be 55 turned about the longitudinal axis of the

mold and at an angle to the tilting movement.

G represents a supporting-head which is capable of turning in a vertical plane and which is provided at opposite ends with bearings h h'. The front mold-section or cover B is rigidly secured to this head by an externally-screw-threaded boss h², arranged on the front bearing h and engaging with an internally-threaded opening formed centrally in 60 the cover or face-plate, as shown in Fig. 3.

I represents a main shaft journaled lengthwise in the bearings of the supporting-head and projecting at its front end beyond the front bearing h. The bottom section of the 70 mold preferably consists of two plates f f, arranged lengthwise side by side, a cross-piece f', connecting the plates near their front ends, and a hub f², connecting the rear ends of the plates. The hub of the bottom section is secured upon the front end of the shaft by a transverse pin f³, and the rear ends of its plates fit against the front of the face-plate or cover-section sufficiently close to form a 75 tight joint between the same.

The inner body-section C rests at its longitudinal edges on the bottom plates f f, and its rear end bears against the face of the cover-section B. The inner section C is preferably held in engagement with the cover by a hasp 80 c, hinged on the cross-bar of the bottom section and engaging with a pin depending from the adjacent part of the inner body-section. In order to prevent the inner body-section from being lifted from the bottom section, 85 the latter is provided on the front ends of its hub and cross-bar with shoulders or seats, which are engaged by hooks or pins c' on the under side of the inner body-section, as shown in Fig. 3. Upon disconnecting the 90 hasp c and pin the inner body-section can be moved lengthwise on the bottom section for connecting or disconnecting the hooks c' and seats of the same.

In order to permit of handling the inner 100 body-section after the same has become heated by the molten metal, the same is provided with a handle c², which is connected by a wooden shank with the front end of the inner body-section. The outer body-section 105 D is arranged concentrically with the inner section C and rests at its longitudinal edges on the bottom plates, while its front end is provided with an internal flange d, which fits over the front part of the inner section. The 110

outer body-section is held against lengthwise movement on the bottom section by dowel-pins d' , arranged on its longitudinal edges and engaging with corresponding openings in the bottom section, as shown in Figs. 5 and 9. The outer body-section is also prevented from being lifted from the bottom and inner body-sections by two hasps d^2 , hinged on the front end of the bottom section and engaging over pins at the front end of the outer body-section. For the purpose of preventing the outer body-section from sticking to the casting and permitting the same to be readily detached this section is divided lengthwise into two parts d^3 , d^4 . These parts are connected on their outer side by two elastic bows or arches j , j , of metal, which are sufficiently rigid to hold the parts normally in position, but permit the same to yield when expanded by the heat of the metal poured into the mold.

j' represents transverse dowel-pins arranged in one part of the outer body-section and engaging with corresponding sockets in the companion part for maintaining the same in alignment. The outer body-section is manipulated by means of two grips or handles j^2 , of wood, which connect the outer parts of the arches j . For the purpose of increasing the radiation of the outer body-section and hasten the cooling of the casting each part of the section is provided with a plurality of transverse ribs j^3 .

The flange-section E of the mold consists of a peripheral flange e and a radial flange e' , projecting inwardly from the front edge of the peripheral flange. The opposite ends of the flange-section rest on the bottom plates, while the rear edge of its peripheral flange bears against the face of the cover and the inner edge of its radial flange bears against the rear edge of the outer body-section, as shown in Figs. 6 and 8. Longitudinal displacement of the flange-section is prevented by dowel-pins k , arranged at opposite ends of the flange-section and engaging with openings in the bottom section. The flange-section is detachably connected with the bottom section by hasps l , hinged on opposite sides of the bottom section and engaging with pins on the flange-section, as shown in Figs. 1, 2, and 6.

In order to prevent the flange-section from adhering to the casting and enable the same to be removed from the same, this section is divided axially into two parts l' , l' , which are yieldingly connected by a strap m of elastic metal applied transversely to the outer side thereof. An elastic handle m' is also connected with the parts of the flange-section for manipulating the same.

When the several parts of the mold are assembled, the inner and outer body-sections, together with the bottom plates, form the cavity in which the semicylindrical body A

of the half-bearing is cast, while the flange-section and cover-section form that part of the mold-cavity in which the flange a of the half-bearing is cast.

For the purpose of equalizing the cooling of the metal in the mold and compensating for any variation in thickness or peculiarity in the form of the casting and also for hardening the same where necessary the mold is constructed so as to produce a differential chilling effect on the casting according to the specific conditions.

In the half-bearing casting which is produced in the mold shown in the drawings the metal of the flange a is thicker than the body A. For causing this casting to cool uniformly the cover, the bottom, and the outer body-sections are made of iron, the inner body-section is composed of a metal alloy containing copper and zinc, and the flange-section is made of substantially pure copper. Owing to the fact that pure copper has a greater chilling effect than a copper alloy, the flange section of the mold exerts a greater chilling effect on the thick flange of the casting than that effected by the inner body-section of the mold on the thin body in the casting, whereby the casting is chilled practically uniform throughout. By constructing the mold so that the chilling effect of the same on the casting varies according to the variation in the thickness of the casting a casting of this kind can be produced which is practically free from shrinkage strains, and consequently not weakened or cracked so as to be unserviceable. Inasmuch as the copper alloy composing the inner body-section has a greater chilling effect than the outer body-section of cast-iron the inner side of the casting is hardened, thereby rendering the same more durable as a bearing.

The different parts of the metal mold do not diffuse or radiate the heat as fast as it is abstracted from the casting. Each part of the mold is therefore made of such a thickness that it will absorb all the heat which it abstracts from the casting and cool the latter sufficiently without depending upon any radiation of heat from the mold. The different parts of the mold are represented in the drawings of a thickness sufficient for this purpose. If the parts of the mold were not made thick enough to absorb the bulk of the heat of the casting, shrinkage strains would develop before the casting is cooled.

The molten metal for producing the casting is fed into the mold-cavity through a gate or inlet-passage n , which is formed in the cover-section on one side of its center. The molten metal is supplied from a tank or reservoir N , which is mounted on the supporting-head G in rear of the cover B. This reservoir is preferably constructed of an outer body n' , of iron, and an inner insulating-lining n^2 , of asbestos or similar fireproof mate-

rial, which lining preferably extends through the gate or outlet-opening in the mold-cover B. The metal body of the reservoir has the required strength to support the molten metal, and the asbestos lining protects the reservoir-body from the destructive action of the molten metal. The latter is also protected from the chilling effect of the metal reservoir-body, thereby maintaining the metal in a molten condition during the time that the same is being poured into the mold. Upon filling the mold all parts of the same excepting the cover are turned about the axis of the mold, so that the level of the molten metal in the mold is always in line with the gate, and the mold is also gradually tilted, so that the end opposite the gate descends during the filling operation. By thus moving the mold the metal enters the same without any free fall, thereby preventing the intermingling of the molten metal with the air, and consequently reducing oxidation to a minimum, and that part of the mold remote from the gate is also filled in advance of the part near the gate, whereby full and perfect castings are produced. As the mold is turned the rear edges of the bottom plates and the flange-section are firmly held in contact with the face of the cover by a spring o. This spring is mounted on the main shaft and bears at its front and rear ends, respectively, against the front bearing h and an adjusting-sleeve o'. The latter has a screw connection with a shell o², secured to the shaft. By turning the adjusting-sleeve forward or backward the tension of the spring o may be adjusted for holding the rotary parts of the mold against the cover sufficiently firm to produce a tight joint between these parts and prevent the escape of any molten metal between the same. This spring also forms a yielding connection between the rotary parts of the mold and the disk, which permits the parts to expand lengthwise under the effects of the heat of the molten metal, thereby preventing crimping and interference with the free movement of the rotary parts of the mold with reference to the non-rotary cover.

The mechanism whereby the compound rotary and tilting movement is imparted to the mold is constructed as follows:

P represents a pedestal or standard, and Q a saddle mounted on top of the pedestal. This saddle is provided with an upwardly-projecting arm q, to which the supporting-head is pivotally connected on its under side by a horizontal pivot-bolt q'. Upon this pivot the supporting-head and the mold are turned in a vertical plane for tilting the mold as the filling of the same progresses. At the rear end of the main shaft the same is provided with a hand-wheel R, whereby the shaft and the rotary parts of the mold may be turned quickly. For the purpose of enabling the mold to be turned with a slow

steady motion and also for obtaining the requisite power to overcome the friction of the molten metal against the cover a worm-gearing is provided, of which the worm-wheel s is secured to the main shaft between the hand-wheel R and its rear bearing h', and the worm s' is movable vertically into and out of engagement from the under side of the worm-wheel. The worm is secured to the inner end of a short transverse shaft s², which is provided at its outer end with a hand-crank s³ for turning the same. Between the worm and crank the transverse shaft is journaled in a bearing t on the rear arm of a rock-lever T, which latter is pivoted by a screw t' on the side of the supporting-head, so as to turn in a vertical plane. The front arm of the worm-carrying lever moves in a guide t² on the supporting-head.

U represents a spring whereby the lever T is turned in the direction for engaging the worm with the worm-wheel. This spring is preferably connected with the front arm of the worm-supporting lever and the supporting-head, as shown in Figs. 1, 2, and 3. v represents a depending finger secured to the front arm of the worm-supporting lever and adapted to engage a stop v' on the saddle for disengaging the worm from the worm-wheel.

While the mold is arranged in a horizontal position, or nearly so, the worm is disengaged from the worm-wheel, as shown in Fig. 1, whereby the shaft can be turned quickly by means of the hand-wheel for bringing the rotary parts of the mold into the desired position. Upon tilting the mold preparatory to pouring the molten metal into the same the worm-carrying lever moves away from the stop v', which permits the spring v to shift the lever for carrying the worm into mesh with the worm-wheel, as shown in Fig. 3. While the parts are in this position the mold may be turned slowly through the medium of the worm and worm-wheel for moving the front end of the mold-cavity past the gate in the cover.

The mold is moved quickly from its horizontal inoperative position into a sufficiently-inclined position to cause the metal to flow freely from the reservoir into the mold, and thereafter the increasing tilting movement of the mold is continued slowly and in the same measure as the filling of the mold proceeds. The tilting movement of the mold after the pouring of the metal into the same begins is preferably effected automatically by mechanism which is connected with the mold-turning mechanism. The means for this purpose shown in the drawings consists, essentially, of a crank w, arranged at the rear end of the main shaft, a rock-arm X, pivoted at its front end on a hanger x, depending from the rear side of the saddle, a link Y, connecting the rear end of the rock-arm X with the crank w, and a stop device Z, which

limits the movement of the rock-arm X. The link is preferably constructed in the form of a turnbuckle, so that the same may be adjusted. A handle y is attached to the link for convenience in shifting the mold quickly from its inoperative position to the position in which the filling of the mold begins and again restoring the same into its inoperative position. The stop device consists, preferably, of a guide-rod z, pivoted at its upper end on the saddle, while its lower end passes through a swivel z' on the rock-arm and screw-nuts z² z³, arranged on the rod above and below the swivel. The mold is preferably counterbalanced by a weight x', attached to the rock-arm.

Preparatory to commencing the casting operation the mold and connecting parts are shifted into the horizontal position shown in Fig. 1, and the mold is turned so that the gate of the reservoir opens into the bottom part of the mold at one side thereof, as shown in Fig. 6. In this position of the parts the worm is disengaged from the worm-wheel, the crank w is in its uppermost position, and the rock-arm X rests in its lowermost position on the lower nuts Z³ of the guide-rod. While the parts are in this position, a charge of molten metal is delivered into the reservoir, and then the latter, together with the mold and connecting parts, is tilted quickly into the position shown in Fig. 3, in which the metal flows freely from the reservoir into the mold, the extent of this quick movement being limited by the upper screw-nuts z², which are engaged by the swivel of the rock-arm X.

As the parts are tilted into this position the worm is moved into engagement with the worm-wheel. Upon now turning the crank s¹ in the proper direction the mold is slowly turned one half-rotation from the position shown in Fig. 6 to the position shown in Fig. 7, whereby the mold-cavity is moved the entire extent of its rear end past the filling-gate, and the metal is poured successively into all parts of the mold. The movement of the parts is sufficiently slow that the gate always remains substantially on a level with the metal in the mold, whereby the metal is prevented from falling freely in passing from the gate into the mold-cavity. At the same time that the mold is being turned it is further tilted, so that its front end descends until the axis of the mold is arranged at an angle, indicated by the broken lines I I, Fig. 3, whereby the front part of the mold which is remote from the filling-gate, is filled in advance of the rear part of the mold which is nearer the gate, and the unfilled part of the mold-cavity always flares toward the filling-gate, thereby affording a free inlet of metal into the mold until the same is entirely filled, permitting of producing a casting which is full and perfect. This automatic tilting of the mold is effected by the crank w, which

upon making a half-turn from its standing to a depending position while the link is held by the attendant in its uppermost position causes the mold to be tilted an extent equal to the length of the crank w in addition to the initial tilt, which is given the mold preparatory to commencing pouring of the metal. The upper end of the link Y is preferably connected with the crank w by a bolt and slot y', as shown in Fig. 4, which permits the throw of this crank to be varied, as may be required. After the casting is finished the parts are returned to their normal position, whereby the worm is disengaged from the worm-wheel, permitting the mold to be turned quickly by means of the hand-wheel, so that the outer body-section and the flange-section of the mold are uppermost, as shown in Fig. 1. The casting is now removed from the mold by detaching the flange-section and inner and outer body-sections from the bottom section. These parts after being cooled, if required, are replaced on the bottom section of the mold preparatory to making the next casting.

The outer body-section has a tendency to stick to the finished casting and must be forcibly removed therefrom. For permitting this to be done readily a lifting-screw f¹ is arranged in an opening in the bottom plate underneath one side of the outer body-section. Upon tightening this screw after the casting is finished the outer body-section is lifted from the casting, permitting the latter to be subsequently removed from the bottom section and inner body-section.

I do not wish to claim in this application the method which is practiced in making castings, as herein described, as the same forms the subject of another application for Letters Patent of the United States, filed by me February 27, 1902, Serial No. 95,856.

I claim as my invention—

1. A mold for casting an article of varying thickness, said mold being constructed entirely of metal and each part thereof having a heat-absorbing capacity corresponding to the thickness of the metal to be cast in the respective part of the mold-cavity, substantially as set forth.

2. A metal-mold for producing a casting having a semicylindrical body and a segmental flange at one end of the body, those parts of the mold forming the outer side and the longitudinal edges of the body and the outer side of the flange being constructed of iron, that part forming the inner side of the body being constructed of an alloy containing copper and zinc, and that part forming the inner side and periphery of the flange being constructed of copper, substantially as set forth.

3. A mold for producing a casting of semi-cylindrical form, comprising an inner semi-cylindrical section, an outer semicylindrical

- section, a flange arranged on one of said semi-cylindrical sections and closing one end of the space between said sections, a cover closing the opposite end of the space between said sections, and a bottom section closing the space between the longitudinal edges of said sections, substantially as set forth. 5
4. A mold for producing a casting of semi-cylindrical form, having an inner semicylindrical section, an outer semicylindrical section arranged concentric with the inner section and provided with an internal flange closing the space between one end of the inner and outer sections, a cover closing the 10 space between the opposite ends of the inner and outer sections, and a bottom section closing the space between the longitudinal edges of the inner and outer sections, substantially as set forth. 15
5. A mold for producing a casting having a semicylindrical body and a peripheral flange at one end, consisting of an inner semicylindrical section, an outer semicylindrical section arranged concentrically with the inner 20 section and having an internal flange at one end which engages with the corresponding end of the inner section, a crescent-shaped flange-section consisting of a peripheral flange and a radial flange engaging the opposite edge of said outer section, a bottom section engaging with the longitudinal edges of the inner and outer sections and the ends of the flange-section, and a cover engaging with 25 said peripheral flange and the corresponding ends of the inner and bottom sections, substantially as set forth. 30
6. A mold for producing a casting having a semicylindrical body and a peripheral flange at one end of the body, consisting of an inner semicylindrical section, a divided outer semicylindrical section arranged concentrically with the inner section and forming with the latter the mold-cavity in which said body is cast, an elastic connection between the parts 40 of the divided outer section, a divided flange-section forming the mold-cavity in which said flange is cast, and an elastic connection between the parts of the divided flange-section, substantially as set forth. 45
7. A mold for producing a casting having a semicylindrical body and a peripheral flange at one end of the body, consisting of a bottom section, inner and outer semicylindrical body-sections detachably connected with the bottom section, a flange-section engaging with the outer body-section and the bottom section and detachably connected with the latter, and a cover engaging with the flange-section, the inner body-section and the bottom section, substantially as set forth. 50
8. A sectional mold having one part rotatable relatively to the other, and a spring operating to draw said parts together in the direction of the axis of rotation, substantially 55 as set forth. 60
9. A sectional mold having a body provided with a semicylindrical mold-cavity, and a cover engaging one end of said body and forming part of the inner or casting surface of the mold and provided with a gate through which the metal is poured into the mold-cavity, one of said mold members being rotatable relatively to the other for bringing the gate opposite different parts of said cavity, substantially as set forth. 70
10. A sectional mold having a body provided with a semicylindrical mold-cavity and a cover arranged at the filling end of said cavity and provided with a gate, said body being rotatable with reference to said cover 80 for moving the filling end of its cavity past said gate, substantially as set forth. 75
11. The combination of a support, a mold-body pivoted on said support, and a cover for closing the mold-cavity in the body, said cover being secured to said support and provided with a gate leading into said cavity and said body being rotatable relatively to the cover for bringing different parts of its cavity opposite said gate, substantially as set forth. 85
12. The combination of a support, a shaft journaled in the support, a mold-body secured to the shaft, and a cover closing the cavity in said body and provided with a gate leading into said cavity, said body being rotatable relatively to the cover for bringing different parts of its cavity opposite said gate, substantially as set forth. 90
13. The combination of a support, a shaft journaled in the support, a mold-body secured to one end of the shaft, a hand-wheel secured to the opposite end of the shaft, and a cover for closing the cavity in the mold-body, said cover being secured to said support and provided with a gate leading into 100 said cavity and said body being rotatable relatively to the cover for bringing different parts of its cavity opposite said gate, substantially as set forth. 105
14. The combination of a support, a mold-body pivoted on the support, a cover for closing the cavity in said body secured to said support and provided with a gate leading to said cavity, and a worm-gearing for rotating said mold-body relatively to the cover for 110 bringing different parts of its cavity opposite said gate, substantially as set forth. 115
15. The combination of a support, a shaft journaled in said support, a mold-body secured to said shaft, a cover for closing the cavity in the mold-body secured to said support and provided with a gate leading into 120 said cavity, a spring interposed between said support and a sleeve on the shaft for drawing the mold-body against said cover, a hand-wheel for turning the shaft quickly, and a worm-gearing for turning the shaft slowly, substantially as set forth. 125
16. The combination of a mold comprising a body having a mold-cavity and a cover 130

6
having a filling-gate opening into said cavity, means for tilting the body and cover together in one direction, and means for turning the body in another direction relatively to the 5 cover for bringing different parts of the cavity opposite the gate, substantially as set forth.

17. The combination of a support, a head pivoted horizontally on said support, a mold-body pivoted on said head at an angle to the pivot between the support and head and provided with a mold-cavity, a cover fixed on said head and having a gate opening into said mold-cavity, and means for simultaneously 10 tilting the head on said support and turning the body relatively to the cover for bringing different parts of its cavity opposite said 15 gate, substantially as set forth.

18. The combination of a support, a head pivoted horizontally on said support, a shaft journaled in said head at right angles to the pivot connecting said head and support, a mold mounted on said shaft, a crank connected with said shaft, and a link connecting said 25 crank with a normally stationary part on said support, substantially as set forth.

19. The combination of a support, a head pivoted horizontally on said support, a shaft journaled in said head at right angles to the 30 pivot connecting said head and support, a mold mounted on said shaft, a crank connected with said shaft, an arm pivoted on said support, a link connecting said crank and arm, and a stop device for limiting the 35 movement of said arm, substantially as set forth.

20. The combination of a support, a head pivoted horizontally on said support, a shaft journaled in said head at right angles to the 40 pivot connecting said head and support, a mold mounted on said shaft, a crank connected with said shaft, an arm pivoted on said support, a link connecting said crank and arm, and a stop device for said arm consisting 45 of a rod pivoted on said support and passing

through a swivel on said arm, and screw-nuts arranged on said rod on opposite sides of the swivel, substantially as set forth.

21. The combination of a support, a head pivoted horizontally on said support, a shaft 50 journaled on said head, a mold mounted on the shaft, a worm-wheel secured to the shaft, a bearing movably mounted on said head and carrying a worm, and means for engaging said worm with and disengaging the same 55 from the worm-wheel, substantially as set forth.

22. The combination of a support, a head pivoted horizontally on the support, a shaft 60 journaled on said head, a mold mounted on the shaft, a worm-wheel secured to said shaft, a rock-lever mounted on said head, a worm journaled on said lever and provided with a crank, a stop for turning said lever in one direction upon depressing said head, 65 whereby the worm is disengaged from said worm-wheel, and a spring for turning said lever in the opposite direction upon raising the head, whereby the worm is engaged with said worm-wheel, substantially as set forth. 70

23. The combination of a mold, a filling-gate for the same, means for simultaneously tilting the mold and gate, and means for moving the mold and gate one relatively to the other while being tilted, substantially as 75 set forth.

24. The combination of a mold, a filling-gate for the same, means for simultaneously tilting the mold and gate, means for moving the mold and gate one relatively to the other 80 while being tilted, and means for yieldingly drawing the mold and gate together, substantially as set forth.

Witness my hand this 24th day of November, 1902.
